UNITED STATES PATENT OFFICE.

WALTER W. HARTSOUGH, OF MINNEAPOLIS, MINNESOTA.

EXCAVATING TRUCK.

1,315,666.

Specification of Letters Patent.

Patented Sept. 9, 1919.

Application filed December 1, 1916. Serial No. 134,263.

To all whom it may concern:

Be it known that I, WALTER W. HARTSOUGH, a citizen of the United States, residing at Minneapolis, in the county of 5 Hennepin and State of Minnesota, have invented certain new and useful Improvements in Excavating-Trucks; and I do hereby declare the following to be a full, clear, and exact description of the invention, such 10 as will enable others skilled in the art to which it appertains to make and use the same.

My invention has for its object to provide an extremely simple and highly efficient excavating truck, so-called, capable of a large range of use and adapted not only to dig up its own load from the ground, but to carry the same to a distant point and there dump the same in a pile or distribute 20 the same along the line of travel, as may be desired. Generally stated, the invention consists of the novel devices and combinations of devices hereinafter described and defined in the claims.

25 This excavating truck is provided with a large scoop that is primarily open at both ends and is arranged to be moved into a forwardly inclined position to excavate or pick up its load, to be elevated to carry the 30 load, and to be given a backward inclination to discharge its load from the rear end thereof. The invention also involves various other important features, as will hereinafter appear.

35 In the accompanying drawings which illustrate the invention, like characters indicate like parts throughout the several views.

Referring to the drawings:

Figure 1 is a side elevation of the improved excavating truck, some parts being broken away;

Fig. 2 is a plan view of the same, some parts being sectioned on the line 2—2 of Fig. 1;

45 Fig. 3 is a section taken on the line 3—3 of Fig. 1;

Fig. 4 is a section on the line 4—4 of Fig. 2; and

50 Fig. 5 is a view corresponding to Fig. 4 but showing the scoop in its dumping or discharging position.

The truck may have either three or four wheels, but as shown, it is provided with large front wheels 6 and a centrally located 55 rear caster wheel 7. The front wheels 6

are journaled on short axles 8 mounted in bearings 9 on the upright columns 10 and supplemental columns 10^a. At their lower ends, the columns 10 are rigidly secured to the side beams of a rectangular frame 11. 60

These uprights 10, for an important purpose, are made of channel beams set with their channels facing inward, and the horizontal side bars of the frame 11 are likewise made of channel beams set with their 65 channels facing inward. The columns 10 and 10^a are rigidly connected at their upper ends by a cross beam 12, and the ends of this beam are connected to the upper 70 ends of oblique truss beams 13, the lower 70 ends of which are rigidly secured to the rear ends of the side bars of the frame 11. Rigidly supported at the rear of the truck frame is an upright end plate 14. This end plate, as shown, is rigidly secured to short columns 75 15, the lower ends of which are riveted, or otherwise rigidly secured to the rear ends of the oblique beams 13 and to the rear ends of the side bars of the frame 11, 80 and the upper ends of which are tied to 80 said bars 13 by short brace bars 16. The rear caster wheel 7 is journaled to a cast bracket 17 which, as shown, is hinged to the flanges of upper and lower cross angles 18, shown as riveted, respectively, to the 85 upper and lower edges of the back plate 14.

The lower ends of the supplemental columns 10^a are rigidly tied to the intermediate portions of the oblique bars 13 by brace bars 20. In this way there is formed a rigid 90 rectangular frame within which is movably supported a large scoop, or excavating receptacle 21. This scoop has a flat bottom and parallel side plates and is open, both 95 at front and rear. Its front edge is made sharp and in some instances, might be provided with teeth, if found desirable. It is supported for a peculiar motion, as follows:

Applied to its side plates and standing 100 outward therefrom, are roller-equipped studs 22 and 23, the former of which work in the channels of the columns 10 and the latter of which work in channels of the side bars of the frame 11. The roller-equipped studs 22, instead of being directly applied to the sides of said scoop, are directly applied to metal straps 24, which, in turn, are riveted to the front side portions 105 of the said scoop. Under its own weight, 110

the scoop will tend to drop into its lowered excavating position shown by full lines in Fig. 1. It is arranged to be lifted by cables 25 attached to the front portion of the sides thereof at their lower ends, and at their upper ends, to a windlass drum 26 secured on the windlass shaft 27 mounted in suitable bearings on the upper ends of the pedestals 10. Here it may be noted that these windlass drums 26 are tapered and have spiral channels so arranged that the greatest force will be exerted through the cables in effecting the initial lift of the scoop. An accelerated winding speed will be produced as the scoop is raised. This causes the cable lifting device to do its hardest work slowly and, then to make up for lost time by increasing its speed after its hardest work has been done.

Obviously, when the front end of the scoop is first raised, into the position shown by full lines in Fig. 1, little or no horizontal travel will be given to the rear end of the scoop, so that the open rear end of the said scoop will remain close to the rear end plate 14 until after the front end of the scoop has been raised far enough to throw the bottom of the scoop into an approximately level position and clear above the surface of the ground. When the scoop is raised into such position, its open front end is brought just in the rear of an upright front end plate 28 which is fixed to the side bars of the truck frame 11, and extends completely across in front of the scoop. When the scoop is thus raised into an approximately horizontal position, or even into a position inclining slightly backward, its rear end will be closed by the rear end plate 14, and its front end will be nearly or quite closed by the front end plate 28, so that the scoop then affords a very serviceable carrying receptacle.

When the front end of the scoop is further raised, the extreme front edge of its bottom plate will move nearly on a vertical line until after it has passed above the upper edge of the front end plate 28, but thereafter it will be projected slightly forward. Under releasing movement of the front end of the scoop, the rear rollers 23 will travel in the side bars of the frame 11 and the rear end of the scoop will move forward and away from the rear end plate 14, thus causing or adapting the scoop to dump its load from the rear end.

For some purposes, it is desirable that the scoop have a removable or displaceable gate at its rear end. Such a gate 29 as shown has mounted guide-ways 30 formed on the inner surface of the rear ends of the sides of the said scoop 21.

Obviously, when the gate 29 is in place, and the scoop is inclined backward by raising of the front end thereof, the load will not be dumped until the gate 29 has been

removed or raised, and then the load will be suddenly discharged. Where it is desirable to distribute the load gradually over a considerable surface of a road, or the like, the gate will not usually be employed, but the discharge of the load will be regulated simply by gradually increasing the backward inclination of the scoop and the resulting opening of the rear end thereof by separation from the fixed back plate 14.

Driving connections are provided whereby, under forward advance of the truck, the windlass shaft 27 will be driven from one of the truck wheels thereof. These connections are preferably as follows:

Secured to the hub of one of the large wheels 6 is a large sprocket wheel 31 that is alined with a smaller sprocket 32 that is secured to the common sleeve-like hub of a pair of reversely facing beveled gears 33 mounted to rotate freely and slide laterally on a spindle 34 rigidly secured to the upward end portions of the adjacent pedestal bars 10 and 10^a. The beveled gears 33 are adapted to be engaged, one at a time, but at will with a beveled pinion 35 that is secured to a short horizontal shaft 36 mounted in a bearing bracket 37 on the upper ends of the adjacent pedestal bar 10^a and brace bar 13. A worm 38 is secured on the shaft 36 and meshes with a worm gear 39 that is secured to one projecting end of the windlass shaft 27. At one end, the worm shaft 36 has a projecting annular shank with which a crank 40, indicated by dotted lines in Fig. 1, is adapted to be applied, for use, when it is desired to raise or lower the front end of the scoop by hand power.

When both gears 33 are disengaged from the pinion 35, the worm and gear will lock the scoop in any adjustment in which it may be set, and may then, if desired, be moved by operation of the crank 40.

The common hub of the gears 33 and sprocket 32 has a grooved channel that is engaged by one end of a bell crank shipper lever 41 that is pivoted to a suitable support on the bracket 37. The extended arm of this bell crank shipper lever 41 stands in such position that it will be engaged and caused to move the two gears 33 into neutral or released positions whenever the front end of the scoop is raised to its extreme limit shown by dotted lines in Fig. 1. Such engagement of the bell crank 41 by the adjacent side plate of the scoop will move the gears 33 from left toward the right, in respect to Fig. 3, and hence, will disengage the right hand gear 33 from the pinion 35 and instantly stop the winding action of the windlass.

The elevation of the scoop will be caused by engaging the right hand gear 33 with the pinion 35 and the lowering movement of the scoop will be produced by engaging the left hand gear 33 with said pinion. A draw

5 bail 42 is hinged to the front end of the truck frame 11 and is adapted, when desired, to be attached to a pole 43 indicated by dotted lines in Figs. 1 and 2. A draft bail 44 is
6 also shown as hinged to the rear end of the truck frame 11, so that when desired, several of these grading trucks may be connected together in a train.

7 This so-called excavating truck is capable
10 of a large range of use. It will be very efficient for use in making excavations for buildings, for example, where it is usually necessary, not only to excavate the dirt, but to carry the same to a remote point. Obviously, the device serves not only the purpose of an ordinary scraper, but also that of a conveying and dumping or distributing truck, and does this without requiring loading other than that in the act of excavating
15 or primarily picking up the dirt.

20 The device is also highly efficient for use in grading roads, both for removing dirt with a planing action or for hauling dirt and gravel onto the roads or depositing the same in the form of a dressing or in depressions to be filled. It will also be found very useful in digging up packed snow and ice from city streets, and for carrying the same to a dumping point.

25 30 The device, as will be understood from the foregoing description, will operate either in soft soil or hard ground. In truing up roads, it may be used as a sort of planer in cutting off high spots and may then be used as a distributor to redeposit the dirt in low spots.

35 It may be further noted that in raising the front end of the scoop or scraper, either to bring the same into a carrying position
40 or to set the same at a backward inclination for discharging of the load, only approximately one-half of the load is lifted, the other half or more being supported on the rollers 23. Furthermore, as the front end
45 of the scoop is raised higher and higher, more and more of the load is transferred onto the rollers 23 and the lifting of the load is aggressively made easier and easier, as the cables are wound onto the large portions
50 of the conical drums 26, and hence, is given an accelerated lifting movement.

55 What I claim is:

60 1. The combination with a truck, of a scoop, scoop guides supported by the frame of said truck, means for raising and lowering the scoop on said guides, the said scoop guides being at an angle to each other and arranged positively to shift the angle of the scoop so that when in extreme lowered position, the scoop will be forwardly inclined to pick up the load, when in an intermediate position will be horizontal, and when in an extreme raised position, will be backwardly inclined to discharge the load.

65 2. The combination with a truck, of a

scoop that is primarily open at both ends, and connections supporting said scoop from said truck for raising and lowering movements, and for adjustments into both forwardly and rearwardly inclined positions, 70 the truck frame having a rear end plate serving to close the rear end of said scoop when the latter is lowered to pick up a load and elevate and carry a load, but from which said scoop is endwise movable when 75 given a backward inclination.

3. The combination with a truck having both upright and approximately horizontal scoop guides, of a scoop having front end guide devices working in said upright guides 80 and rear end guide devices working in said horizontal guides, and means for raising and lowering the front end of said scoop, said scoop, when lowered having a forward inclination, and when elevated, having a 85 backward inclination.

4. The combination with a truck having both upright and approximately horizontal scoop guides, of a scoop having front end guide devices working in said upright 90 guides and rear end guide devices working in said horizontal guides, means for raising and lowering the front end of said scoop, said scoop, when lowered, having a forward 95 inclination and when elevated having a backward inclination, the said scoop being primarily open both at front and rear ends, and a rear end plate fixed to the rear portions of the truck frame and serving to close the rear end of said scoop when the latter 100 is lowered, but away from which the rear end of said scoop is moved when raised and given a backward inclination.

5. The combination with a truck having both upright and approximately horizontal 105 scoop guides, of a scoop having front end guide devices working in said upright guides and rear end guide devices working in said horizontal guides, means for raising and lowering the front end of said 110 scoop, said scoop, when lowered, having a forward inclination and when elevated having a backward inclination, the said scoop being primarily open both at front and rear ends, a rear end plate fixed to the rear 115 portions of the truck frame and serving to close the rear end of said scoop when the latter is lowered, but away from which the rear end of said scoop is moved when raised and given a backward inclination, 120 and a rear end plate applied to the front portion of the truck frame in position to approximately close the front end of said scoop when the said scoop is raised into a load carrying position.

6. The combination with a truck, of a scoop that is primarily open at both ends, and connections supporting said scoop from said truck for a compound endwise and pivotal movement from one position in 130

4
which it is forwardly inclined for taking up load to another position into which it is rearwardly inclined for dumping the load, the said truck frame having a rear end plate serving to close the rear end of said scoop when the latter is lowered to pick up its load, but away from which the rear end of said scoop is moved when said

scoop is rearwardly inclined to discharge its load.

10

In testimony whereof I affix my signature in presence of two witnesses.
